(57) **CLAIM**

The ornamental design for an ambient light otoscope, as shown and described.

DESCRIPTION

FIG. 1 is a front-top-right perspective view of an ambient light otoscope showing my new design;

FIG. 2 is a front-top-left perspective view thereof;

FIG. 3 is a front-bottom-right perspective view thereof;

FIG. 4 is a rear-bottom-right perspective view thereof;

FIG. 5 is a rear-bottom-left perspective view thereof;

FIG. 6 is a front elevational view thereof;

FIG. 7 is a rear elevational view thereof;

FIG. 8 is a top plan view thereof;

FIG. 9 is a bottom view thereof;

FIG. 10 is a right-side elevational view thereof; and,

FIG. 11 is a left-side elevational view thereof.

The broken lines depict environment and form no part of the claimed design.
